UNITED STATES PATENT OFFICE.

CESARE BARBIERI AND PAUL CARPENTER, OF CHICAGO, ILLINOIS.

MACHINE FOR MAKING PHOTOGRAPHIC PRINTS.

Application filed January 19, 1921. Serial No. 438,418.

Our present invention relates in general to machines for making photographic prints, and more particularly to machines for producing prints which require treatment by fluids subsequent to exposure to light, and has special reference to the construction of an improved type of so-called "continuous machine".

The principal objects of our present invention are the provision of a compact machine by means of which photographic prints may be produced most efficiently, with great rapidity and at small expense; the provision of improved means for feeding the sensitized paper and the tracings to the machine; the provision of improved means for the prevention of the fogging of said sensitized paper prior to or during its passage over the printing plate; the provision of a photo-printing device having an improved arrangement of opaque and transparent surfaces; the provision in a machine of the present character of improved means for removing air from between the negative and the sensitized paper, and from between the negative and the printing plate; the provision of improved means for securing contact between the negative and paper and the plate; the provision of improved means for tensioning the paper during its passage through the machine; the provision of combined spring and gravity actuated devices for such purpose, and generally, to improve, cheapen and simplify the construction of machines for making photographic prints embodying one or more of the several steps referred to, together with such further objects as will hereinafter appear.

In attaining the foregoing objects, and certain additional benefits and advantages to be below disclosed, we have provided the construction illustrated in the accompanying drawings, wherein:—

Figures 1 and 2 are, respectively, a side elevational view, partly in section, and a top plan view with certain parts removed for the sake of clarity, illustrating a preferred form of machine embodying our invention.

On inspection of the drawings it will be observed that we have shown a complete machine for making prints adapted for use in connection with any suitable print treating and drying, and like apparatus, but more particularly apparatus for these purposes as set forth in our Patent No. 1,292,230, dated January 21, 1919.

The several parts mentioned, together with certain auxiliary apparatus, are conveniently supported by parallel frame members 10, 11 suitably spaced apart by the said frame members, the mounting for the parts being substantially duplicated for both sides.

It will be observed that in our printing frame we employ a parti-cylindrical translucent sheet, preferably formed of a sheet 20 of plate-glass bent into the desired form and supported by complementarily curved portions 21 of the frame members 10, 11. As a source of light for the printing, we utilize a suitable number of light emitting bodies here shown as arc-lamps 22 controlled by switches 22^a and carried by a shield 23. To facilitate the trimming and other care of the lamps and cleaning of the plate the shield 23 is hinged between frame portions 24 as indicated at 25. In order to concentrate the rays of the lamps which would otherwise be diffused and ineffective, the shield 23 is provided with a highly refractory surface 23^a, and is curved as shown.

Since the upper portion of the cylinder is relatively inactive photographically, owing to the structure and disposition of the arc lamps, the lower margin of the cylinder is desirably extended forwardly beyond the upper margin thereof, and also upward in aid of the discharge of the tracings to be hereinafter set forth. As a closure against light emitted above the upper margin of the shield, 23, we provide an auxiliary shield 26 hinged as indicated at 27 to the feed guide table to be hereinafter referred to. Since the construction described forms for all practical purposes a closed cylinder, to prevent undue heating of the plate 20, we provide a fan 28 which is desirably of the positively acting type in order to insure proper ventilation of the cylinder and ejection of the heated fumes therefrom.

To the end that the exposed surface of the plate 20 may be varied with consequent variation of the length of time the sensitized paper is exposed to light during its passage over the printing plate 20, we provide movable segmental shields 29 carried in slots 30 in the frame portions 21, whereby portions of the plate may be rendered opaque, thus readily permitting the use of papers of varying degrees of sensitiveness.

For conveying the sheet of printing paper 31 over the plate 20 as it unrolls from the roll 32, and the tracing which is to be copied on such paper we employ a pair of supporting

rollers 33, 34 suitably journaled in the frame 10, 11, mounting thereupon an endless belt 35. For tensioning the belt 35, and assuring contact thereof with the plate 20 the roll 34 5 should be driven somewhat faster than the roll 33, and in further aid of this object we pass the belt over a roller 36 mounted in brackets 37 slidably carried by frame portions 38, turn screws 39, engaging extensions 40, 41 10 formed on the brackets and frame members respectively, being utilized for taking up any slack in the belt.

To insure the desired straight feed of paper from the roll 32 and prevent fogging and loss 15 of sensitiveness due to premature unrolling or loosening of the paper the roll 32 is carried in slots 42 formed in upward extensions 43 of the frame members 10, 11 and above it a gravity pressure roll 44 rides in such slots and bears upon it, forcing it down upon the belt 35 where it passes over the roll 33. Further 20 to prevent fogging of the paper as it moves over the periphery of the roll 33 with its sensitive surface exposed, we provide a shield 45.

As an auxiliary to the insertion of the tracings between the belt 35 and the printing plate 20, we employ a feed guide table 46 supported by the frame members 10, 11, and by 30 which in turn the shields 27 and 45 are conveniently supported.

In order to remove as far as possible all air from between the paper and the tracing, on the one hand, and from between the tracing and the printing plate on the other hand, thus 35 avoiding blank or lightly printed spots, slippages, offsets, and the like, we mount in arms 47 pivotally supported at 48 by the frame members 10, 11, a pressure roller 49, employing for its yieldingly resistant support 40 springs 50 sustained by frame extensions 51.

As has been suggested the lower margin of the plate 20 should be forwardly extended for two reasons, first: to secure, when desired, full 45 benefit of the most efficient light rays given off by the lamps 22; and, second: inasmuch as the tracings will tend to follow the contour of the plate, that they may readily separate from the paper and be discharged upon the 50 delivery table 52, instead of tending to follow the paper around the relatively sharp turn it takes in its movement over the roll 34.

The arrangement just described is also advantageous in that the tracing is discharged 55 immediately at hand, permitting reprinting thereof, if desired, without loss of time, effort, or paper.

The printed paper leaves the roll 34 and moves towards the rear of the machine with 60 its printed sensitized surface downwardly dis-

posed. It is then ready for treatment by water or other suitable fluid.

For actuating the several parts of the machine, we have above described, we provide suitable driving mechanism preferably employing therein as here shown an electric motor 140 having suitable connections as indicated at 141, 142, to a source of current supply (not shown). On the motor shaft 143 we provide a pinion 144 driving a gear 145 on a shaft 146 having a sprocket thereon by means of which the fan 28 is driven through a chain 150 and pinion 151. On the motor shaft 143 we also provide a worm gear 152 driving a worm wheel 153 on the shaft 154 of the roll 34 which shaft through a pair of sprockets 155^a (one not shown) and a chain 155 at the opposite end (see Figure 2) drives the shaft 156 of the roll 33.

Since the fan 28 as well as the several rolls 80 are all driven by the same motor the operation of the device is greatly simplified. Furthermore, inasmuch as the bearings of the members 49, 33, 32, 44, and 47 are substantially in alignment it is apparent that in the construction of a machine embodying our improvements we have provided as far as may be against distortion of the paper in its passage therethrough.

In view of the foregoing specification, it is 90 thought that a more amplified description of the operation of the machine will be unnecessary and that it will be readily understood by those skilled in the art to which our invention pertains.

Having thus described our invention and illustrated its use, what we claim as new and desire to secure by Letters Patent is:—

1. In an apparatus of the character described, in combination with a printing plate, an endless conveyor mounted about the periphery of such plate, and a plurality of driven means for supporting said conveyor, and means for driving members of said driven means at different rates of speed for maintaining said conveyor taut.

2. In an apparatus of the character described, in combination, a translucent printing plate, an endless conveyor mounted about the periphery of such plate, a plurality of supporting means for said conveyor, and means for supporting a supply of paper, a positively actuated means for tensioning said conveyor and gravity actuated means for tensioning the paper as it is fed by said conveyor onto said translucent surface.

In testimony whereof we have hereunto signed our names.

CESARE BARBIERI.
PAUL CARPENTER.
